UNITED STATES PATENT OFFICE

ARTHUR KUHN, OF RECKLINGHAUSEN, GERMANY, ASSIGNOR TO THE FIRM; CARL STILL, OF RECKLINGHAUSEN, GERMANY

DISTILLATION AND LIKE COLUMN

Application filed December 1, 1926, Serial No. 151,998, and in Germany July 16, 1926.

This invention relates to distillation and like columns and more particularly to an improved construction employed in mounting and securing the vapor distributing hoods on the trays or bottom plates of such columns.

These columns are preferably constructed of superposed sections each embodying one or a pair of trays or bottom plates which support a plurality of vapor distributing hoods, and heretofore it has been customary to secure the hoods to the trays by bolting or in some instances by fused metal joints which necessitated a rather troublesome process for their removal. It is, therefore, one of the essential objects of this invention to obviate the difficulties encountered in previous constructions and to provide means which permits the ready insertion and removal of each vapor distributing hood.

Another and very important object is the arrangement of the respective sections and the construction of the vapor passage collars so as to permit the ready insertion and withdrawal of said hoods each radially of the axis of the section.

A further object of the invention which is made possible by my arrangement of the vapor distributing hood is the provision of means which insures a uniform distribution of the liquid over the trays of the column which means is particularly effective in columns utilized for the distillation of ammonia liquor, of benzol and other hydrocarbons, and in washing impure gases. It is also particularly advantageous where there is any deposition of solid materials upon the trays of the columns.

Further objects of the invention will appear as the following specific description is read in connection with the accompanying drawings which forms a part of this application, and in which:

Figure 1 is a vertical axial section, taken on the line 1—1 of Fig. 2.

Figure 2 is a horizontal section taken on the line 2—2 of Figure 1.

As each section of the plurality of sections employed in producing a complete distillation column is identical, the illustration

of one section and a description thereof will be sufficient.

At *a* I have shown one of the sections of a distillation column, and from an inspection of the drawings it will be seen that this section comprises a cylindrical body having a plurality of radially extending flanges *a'* defining openings *r* closed by covers or doors *f* secured in position in any suitable manner as by bolts or otherwise.

The interior of the cylindrical body *a* is provided with an internal annular flange *y* arranged adjacent its base and a similar but narrower flange *x* approximately midway of its height. These flanges, as shown, support the trays *b* and *b'* each of which have arranged radially around the vertical axis thereof the upstanding vapor collar *c*, *c'* which define the vapor passages *c*². These collars are integral with the tray and each extends vertically and is substantially trapezoidal in plan. The collars in addition to being formed integral with the trays are connected to such trays by webs *n*, *n'* having inclined upper surfaces forming ramps, the purpose of which will be described hereinafter.

The tray *b'* is provided in its center with a collar *e'* defining an overflow passage and this collar extends both above and below the trays as clearly shown in Figure 1. It is provided at its upper end with an annular outwardly extending flange *g'* which is bevelled upon its under face as shown. A similarly formed flange *g* is arranged at the bottom end of the collar *e'* also being provided with a bevelled under face.

As shown in Figure 1 the tray *b* is provided with a plurality of overflow pipes *e* which are arranged in plan view adjacent the periphery of the body *a* and between adjoining vapor passages *c*². The upper ends of each of these pipes extend to a height approximately level with the upper end of the collars *c*—*c'*, while the lower end of the pipe extends downwardly to a sufficient distance to project below the upper edge of the collar *e'* on the section next below in the column, and the lower end of the pipe *e* may be of such length as to bring it within close proximity of the tray *b'* in the next lower section of the column.

In Figure 2 the sectioned circles indicated at e^2 represent the lower ends of the pipes e in the next above section of the column.

Each of the collars $c-c'$ have resting thereon and covering the same a vapor distributing hood, and as all of these hoods are identical, a description of one will be sufficient. It is to be also understood that I may employ as many hoods and vapor passages as is found desirable. In the present instance the arrangement shown permits of the use of six on each tray.

As shown in Figure 2 the hoods which are indicated at $d-d'$ on the respective trays $b-b'$ are substantially trapezoidal in plan with their depending walls d^2 substantially parallel with the vertical walls of the collars $c-c'$. Each hood is provided with a pair of internally arranged flanges i extending across the same and connected to the top and depending side walls of the hood so as to form in effect supporting feet for the hood. These flanges i rest upon the upper edges of the collars $c-c'$ and space the top of the hood from such collars a predetermined distance.

The forward end of each hood is provided with an extension which I have indicated at $h-h'$ and is adapted to engage beneath the flanges $g-g'$.

30 The opposite end of the hood, that is, that end adjacent the periphery of the column is provided with an extension $k-k'$ on the respective hoods $d-d'$, which is preferably made in the form of a handle, that is, provided with a finger opening k^2 which permits the operator to handle the hood conveniently. These latter extensions $k-k'$ engage under lugs or internal projections m formed on the doors or cover plates f so that when such 40 cover plates are secured in position each hood will be locked in position on its collar c or c' , the extensions h and h' and k and k' being beneath the flanges $g-g'$ and lugs m , respectively.

45 When it is desired to insert a hood in position, the same is pushed through the opening r and the extension h or h' will ride upon the outer ramp n , and then over the upper edge of the collar c until it reaches the inner portion thereof when it rides down the ramp n' and under the flange g or g' . When the door f is secured in position over the opening r , the lug m will rest upon the top of the extension k or k' thus securing the hood in 50 proper position over the vapor passage. The removal of anyone of the hoods is just in reverse order, the inner extension riding first over the ramp n' and then over the collar of the vapor passage and down the ramp n , the 55 finger opening k^2 in the extension k or k' facilitating the insertion and removal of such hood.

In order that liquid travelling over the 60 trays in either direction may be uniformly distributed and be effectively subjected to the

vapor entering under and issuing from beneath the depending sides of the hoods, I provide V-shaped deflector plates s arranged between adjoining hoods and partially surrounding the depending lower ends of the overflow pipes e . These plates s have their apices directed toward the axis of the column, and it will be seen from an inspection of the drawings that liquor passing from the lower end of the collar or tube e' will flow toward the overflow or outlet pipe e and be brought into contact with the divergent walls of the deflector plates s and carried toward adjoining hoods. Liquor overflowing through pipe e onto tray b' will be deflected by the surfaces of the deflector plates s toward the hood in a like manner. It will be, therefore, seen that liquor flowing in either direction from the overflow pipe e' outwardly or from the overflow pipe e inwardly toward the axis will be directed toward the walls of adjoining hoods. This produces an even distribution of the liquid on all trays and subjects substantially all liquid to the action of the vapor entering under and issuing from beneath the depending side walls of the hoods. It is believed that it will be well understood from an inspection of the drawings that the distributing plates s on the tray b are arranged closely adjacent and partially surround the upper end of the overflow pipe e which is carried by the tray b , while the distributing plates s on the tray b' are arranged so that the depending lower ends of the respective overflow pipes of the next upper tray will be disposed closely adjacent thereto and partially surrounded by the distribution plates s .

From the foregoing it will be seen that I have provided a very simple method of mounting and securing the respective vapor hoods which permits their ready insertion and removal, and also a construction which effectively secures the hoods in position without the employment of bolts or other securing means which involve considerable trouble. It will also be seen that by the arrangement of liquor distribution and the method of securing the hoods with the radial openings for their insertion and removal that 105 cleaning of the various trays in the column is made comparatively easy.

While I have shown and described trapezoidal collars $c-c'$ and hoods $d-d'$ conforming thereto it will be clearly understood that the hoods and collars may be rectangular in outline or in fact any other shape without departing from the invention.

What I claim is:

1. In a column for distillation and like purposes, a tray bearing an overflow element and a vapor collar, a hood arranged in position over the collar, and means, a part of which is on said element, for holding the hood in position.

2. In a column for distillation and like purposes, a tray bearing an overflow element and a vapor collar, a hood arranged in position over the collar, and means, a part of which is formed integral with said element for holding the hood in position.

3. In a column for distillation and like purposes, a tray bearing an overflow element and a vapor collar, a hood arranged in position over the collar, and means including a flange on said element for holding the hood in position.

4. In a column for distillation and like purposes, a tray bearing an overflow element and a vapor collar, a hood arranged in position over the collar, a flange on said element having a beveled under face, and means serving to hold a portion of the hood under the flange and said hood in position.

5. In a column for distillation and like purposes, a cylindrical body having an opening in its side, a tray mounted in said body and having overflow and vapor passage elements, a hood positioned over the last element, means for closing said opening, and means including parts on the closing means and overflow element for holding the hood in position.

6. In a column for distillation and like purposes, a cylindrical body having an opening in its side, a tray mounted in said body and having an element defining a vapor passage therethrough, a hood insertable through said opening and positioned over said passage, and means facilitating the insertion and removal and the proper positioning of said hood over said passage, means for closing said opening, an overflow element, and means carried by said closing means and overflow element for securing the hood in position.

In testimony whereof I affix my signature.
ARTHUR KUHN.
